(57) **CLAIM**

The ornamental design for a fuel dispenser, as shown and described.

DESCRIPTION

FIG. 1 is a front elevational view of a fuel dispenser, showing my new design;
FIG. 2 is a right-side elevational view thereof;
FIG. 3 is a rear elevational view thereof;
FIG. 4 is a left-side elevational view thereof;
FIG. 5 is a top plan view thereof;
FIG. 6 is a bottom plan view thereof;
FIG. 7 is a cross-sectional view thereof taken along line A-A of FIG. 1; and,
FIG. 8 is a front lateral view of the fuel dispenser, including the environment of the article embodying the design as it would be used, the environment including a hose, a hose connector and a handle illustrated in broken lines.
